UNITED STATES PATENT OFFICE.

WALTER WRIGHT, OF SAN FRANCISCO, CALIFORNIA, ASSIGNOR, BY MESNE ASSIGNMENTS, TO UNDERWOOD COMPUTING MACHINE COMPANY, A CORPORATION OF NEW YORK.

BILLING AND COMPUTING ATTACHMENT TO TYPEWRITERS.

Application filed April 20, 1908. Serial No. 428,020.

To all whom it may concern:

Be it known that I, WALTER WRIGHT, a citizen of Great Britain, residing at San Francisco, in the county of San Francisco and State of California, have invented new and useful Improvements in Billing and Computing Attachments to Typewriters, of which the following is a specification.

The object of the present invention is to provide a computing device which can be attached to any standard typewriting machine for the purpose of computing both vertical columns and horizontal or cross totals of the figures as they are written by the typewriting machine in a larger number of columns for a given width than has heretofore been accomplished; and also for varying the widths of the several columns, while economizing space in doing so.

A further object is to provide a mechanism which will admit of vertical and horizontal computation of a large number of columns, and in which the horizontally computing mechanism is adapted for the horizontal computation of columns of any size, and, further, in which the portions of the writing space reserved or assigned for each column may be varied, as desired, to correspond with the actual width of the column to be written therein, thus utilizing to the best advantage the writing space of the paper, so as to accommodate the greatest possible number of columns.

The invention also resides in the novel construction, combination, and arrangement of parts, hereinafter fully specified and particularly pointed out in the claims.

In the accompanying drawing, Figure 1 is a front view, partly in section, of a typewriting machine equipped with my invention; Figure 2 is a broken top plan view of the numeral keys; Figure 3 is a broken section view showing the computing shaft; Figure 4 is a similar view showing the upper transfer shaft; Figure 5 is a broken perspective view showing the key connections; Figure 6 is a longitudinal sectional view of the controlling mechanism; Figure 7 is a sectional view at right angles to Figure 6; Figure 8 is a broken perspective view of the same; Figure 9 is an enlarged top plan view of the escapement; Figure 10 is a cross section of the controlling mechanism; Figure

11 is an enlarged vertical section through the secondary computing mechanism, showing the primary computing mechanism in end elevation; Figure 12 is a broken section through the secondary computing mechanism, looking from the opposite side to Figure 11; Figure 13 is a broken front view of the computing mechanism, the casing being removed; Figure 14 is a broken longitudinal section of the secondary computing mechanism; Figure 15 is a perspective view of one of the computing wheels; Figure 16 is a sectional view of the same; Figure 17 is a perspective view of a transfer wheel; Figure 17^a is a perspective view of a transfer wheel used through the partition; Figure 18 is a perspective view of an operating sleeve; Figure 19 is an end view of the machine; Figure 20 is a broken plan view of the mechanism for transmitting the power; Figure 21 is a sectional view of the same; Figure 22 is a vertical view of the transfer reversing mechanism; Figure 23 is a horizontal section of the main computing reversing mechanism; Figure 24 is a vertical section, of the same; Figure 25 is a vertical detail section showing the lower mechanism for reversing; Figure 25^a is a detail sectional view showing the operating devices for the secondary mechanism; Figure 25^b is a similar view showing the parts in another position; Figure 25^c is an end view of said secondary mechanism; Figure 26 is a plan view of the connection between the computing and secondary mechanisms; Figure 27 is a detail front view of the connector rod and part cooperating therewith; Figure 28 is a plan view of the same; Figure 29 is an enlarged section through the shifter bar; Figure 30 is a front view of a modified form of the invention; Figure 31 is a broken detail front view of a second modification; Figure 32 is a front view of a third modification; Figure 33 is a front view of a fourth modification; Figure 34 is a front view of a modification adapted for machines in which the paper carriage is lifted; Figure 35 is a broken sectional view through the operating shaft; Figure 36 is an enlarged sectional view through the computing mechanism; Figure 37 is a section through the operating frame; Figure 38 is an end view of the same; Figure 39 is a detail per-

spective view of the operating sleeve; Figure 40 is a broken perspective view of the computing shaft and the inner sleeve thereon.

Attachment.—The drawings show the invention as applied to an "Underwood" typewriting machine, but it is to be understood that, with suitable changes, it may be applied to a typewriting machine of any standard construction, and also that the invention may be embodied in the form of a computing machine complete in itself, and not attached to a typewriting machine.

Key connections.—Secured to the frame 1 of the typewriting machine is a vertical plate 2, extending longitudinally of the machine over the key levers 3, (Figure 1); and, secured upon the front of said plate 2, are guides 4 for a slide bar 5, one end of which is formed with two notches 6, into either of which can spring a bent spring arm 7, thereby yieldingly maintaining said bar in either of two positions. The longitudinal movement of this bar, in the manner to be presently described, simultaneously connects all the numeral key levers with the computing mechanism. To move said bar longitudinally, its other end is formed with a recess 8, into which extends an arm 9 on a rock shaft 10, (Fig. 5) to which is secured a lever 11, to one end of which is connected a hanger hook 12 which normally enters a hole 13 in collar 14 on the lever 15 of the shift key 16 of the machine. The machine shown is what is known as a "shift key" machine, in which each of the figure and letter type bars A, B carries two type, of which one 16^a prints normally and the other 16^b only when the shift key is depressed. All of the nine digits are arranged in the typewriting machine to correspond to what is known as the "lower case" characters of the top row of keys 13, so that they may be printed by said keys without using the shift key. Since some other character than a numeral is also carried on each numeral type bar, therefore, if the shift key is used, and a numeral key operated, said other character is then printed. It is therefore desirable at that time to throw the computing mechanism out of action. Upon depressing the shift key 16, the slide bar 5 is evidently moved to the right, and, as will presently appear, this has the effect of automatically disconnecting the numeral key levers from any part of the computing mechanism, so that when any numeral key is used for the purpose of writing an "upper case" character 16^b this is always done without the actuation of the computing mechanism. By the return of the shift key, said slide bar 5 is moved to the left, which then again connects the computing mechanism with the numeral keys, so that when any one of them is depressed the computing mechanism will be actuated.

Through apertures 17 in said slide bar 5

pass links 18, one for each numeral key, having hook-shaped lower ends adapted by the movement of said bar to be moved into or out of engagement with apertured collars 19 secured upon the levers 3 of the nine numeral keys. Each link 18 is connected at its upper end to a bell crank lever 21, another arm of which is connected to a wire rod 22, all of said nine connecting rods 22 passing through a ring 23 (Figs. 1, 8 and 10), secured to the plate 2, said rods being connected respectively to blocks 24 connected to levers 25 pivotally supported by said ring 23. Thus, upon depressing any one of the numeral keys, the outer end of the corresponding lever 25 is moved to the right. The object of this arrangement is to selectively control the action of the computing apparatus, hereinafter described.

In order to operate the numeral keys without actuating the computing mechanism, when desired, there is provided an "Out" key 26, (Figs. 1 and 5), the stem of which key is connected to a bell crank lever 27, loose on the rock shaft 10, and having secured thereto a spring 28' adapted to engage an abutment 29 extending from an arm 28 depending from the lever 11.

A link 30 (Fig. 5) is connected to the lever 27 and to the hanger bar 12, so that the first movement of said lever 27 has the effect of withdrawing the hook 12 out of the hole 13 in the collar on the shift key lever. As this takes place, the spring 28' is compressed between the lever 27 and the abutment 29. When said spring can no longer yield, the lever 27, acting against the abutment 29, causes the rock shaft 10 to rock, so that the slide bar 5 is moved to the right, against the action of the retaining spring 7, which then drops into the left one of the two notches 6, so that the operation of the shift key has now no effect whatever upon the connecting or disconnecting of the numeral keys with the computing mechanism.

To render the key connections again operative, there is provided an "In" key 31, the stem of which is connected to the lever 11, so that the depression of said key 31 moves the slide bar 5 to the left. The spring 28 then restores the key 26 to its normal position, so that the hook 12 again enters the hole of the collar 14 on the shift key lever.

Controller.—Secured on the right hand side of the frame of the typewriting machine is a bracket 33, supporting a vertical plate 34, carrying posts 35, supporting a guide plate 36, having a circular series of holes, through which extend the ends of nine pusher rods 37, pivotally attached to the several bell crank levers 25 (Figs 6 and 7). Having its bearing in the plate 34 is a shaft 38, of a controller 39; which, as will be presently described, is under constant rotational pressure. Stop bolts 40, of which there should be not

less than ten, slide in a circular series of slideways 41 in said controller, which slideways register with the pusher rods, and said bolts project to the left of said controller normally, and until they are displaced by the action of the pusher rods 37. An annular coiled spring 42, which surrounds the controller in a groove therein deep enough to intersect the slideways for the bolts, and which is adapted to engage one or the other of two grooves 43 formed in each bolt yieldingly maintains the bolts in the positions to which they have been moved. When any numeral key has been operated, and the corresponding pusher rod moved through the guide plate, its end impinges upon the end of a stop bolt projecting from the left hand side of the controller and moves said stop bolt to the right from Fig. 6 to Fig. 7, so that its other end then projects from the right hand side of said controller, and said stop bolt, thus projecting, will therefore impinge against a stop wheel 44 and arrest the controller, when the latter after being released, by escapement mechanism to be presently described, has rotated through an angular distance which depends upon the position of the bolt which has last been so actuated, and therefore upon the particular pusher rod and the particular numeral key lever which have last been operated. When the controller so rotates, the projecting end of the last previously projected stop bolt is then, by means of a wedge 45 on the plate 34, and located in the path of the projected stop bolt, returned to its normal position, in which it projects from said controller to the left instead of to the right, and it is retained in that position by the annular coiled spring.

40 Escapement.—Secured upon the front side of said plate 2 is a guideway 46 for a stem 47 (Figs. 6 and 7), the other end of which is pivotally connected to a lever 48 pivoted at 49 upon the ring 23, to the other arm of which lever is secured a spring 50, which normally tends to draw said arm to the left, and therefore said stem to the right. Said stem carries a disk 51, and all of the rods 22 pass through holes in said disk.

When any numeral key has been operated, and thereby the corresponding rod moved to the left, the block 24 by which it is connected to the bell crank lever 25 then abuts against said disk, and carries said disk with it to the left, thus rocking the lever 48. The long arm of said lever is connected at its extreme end by a link 52 with an arm 53 on an escapement shaft 54, so that, by said movement of said lever, said escapement shaft is rocked. Said escapement shaft carries, adjustably two disks 55, 56, spaced apart a short distance, and having respectively formed in their bevelled edges notches or recesses 57, 58, offset from each other, Figs. 8 and 9. Through said plate 34 passes a stop shaft 59, which on the left side of said plate 34, carries the before-mentioned stop wheel 44, which is star-shaped, having points, any of which is adapted to lie in the path of a bolt in the controller which has been projected to the right, and arrest said controller if said stop shaft is then itself held fast and non-rotatable. Secured upon the end of said stop shaft upon the right hand side of the plate 34 is a large star wheel 60, having the same number of points as the wheel 44, a point of which star wheel normally abuts against the first or rear disk 55. Therefore, when any numeral key has been actuated, and thereby the escapement shaft 54 rocked, the disk 55 is thereby moved until the notch 57 therein comes opposite to the point of the large star wheel 60, which can then immediately pass through said recess. This it immediately does, because, as already mentioned, the controller shaft is under constant rotational pressure, so that the previously projected bolt is pressing against a point of the stop wheel 44, tending to turn it, and the shaft 59, and the star wheel 60. After said point has passed through said notch 57, it then abuts against the second disk 56, and the stop shaft is again held from further rotation. The slight movement thus given to the stop wheel 44 allows the bolt arrested thereby to move a very slight distance only, then, upon the release of the numeral key, the escapement shaft 54 returns to its original position, in which position the recess 58 in the second disk now comes opposite to the said bevelled point or arm of the large star wheel 60, which thereupon escapes therethrough, under the pressure of the stop bolt on an arm of the stop wheel 44. This pressure rotates the shaft 59 so that the next succeeding arm of the stop wheel is brought into the path of the last projected bolt, which then impinges against said latter arm, thus continuing the rotational pressure on the stop shaft, rotating said shaft until the next succeeding point of the large star wheel 60 is brought up against the first escapement disk 55, and the parts are then again in their normal position, ready for another operation. It will thus be seen that the extent of movement of the controller shaft is dependent upon the angular position, relatively to the stop wheel, of the pusher rod actuated, and therefore upon the particular numeral key which is operated.

Driving.—It has been already mentioned that the controller shaft is under constant rotational pressure, tending to rotate said shaft whenever released by the escapement mechanism. This rotational pressure is derived from any suitable motor, and for the purpose of illustration I have herein shown an electric motor 61, Figs. 1 and 19 and 21. The shaft 62 of said motor has secured there-

on a head 63, to which are pivoted three weighted governor arms 64, Fig. 21 the ends of said arms being adapted to bear against the inner surface of a cup-shaped head 66 secured upon a shaft 67, so that said arms rotate said shaft by their friction against said inner surface. Said shaft has secured thereon a bevel gear 68 which meshes with a bevel gear 69 on a shaft 70 which extends through the plate 34, and carries on its outer end a gear wheel 71 (Figs. 19 and 20) which meshes with an idle wheel 72 which in turn meshes with a gear wheel 73 upon the controller shaft. It is by this means that the controller shaft is given a constant rotational pressure, always in the same direction, rotating the shaft whenever it is released.

In order to vary the amount of friction transmitted from the rotating shaft, there are provided springs 76, one attached to each governor arm 64, the free end of the spring being adapted to be compressed inwards by a ring 77, the position of which can be adjusted in a direction parallel with the shaft 62 by means of screws 80, which screw through said ring and into arms 82 extending from the head 63. By shifting said ring, said springs are more or less compressed, and tend to variably reduce the pressure of the governor arms 64 against the head 66.

Computing mechanism.—The carriage 74 of the main computing mechanism comprises end plates 75, (Figs. 1, 11, and 26), partitions 370 at every fourth writing space of the typewriter, two longitudinal bars 78, and a casing 79 enclosing the mechanism, cut away to form a longitudinal slot 81, through which the figures are displayed. This computing carriage is supported from the paper carriage 83 by means of arms 84 extending from said paper carriage.

The main computing carriage is made just sufficiently large to contain computing devices in a series corresponding in length with the typewriting line of the machine. Upon the left hand end of the frame of the machine is secured a bracket 87 which supports a plate 88 Fig. 1, at a distance from the plate 34 not less than the length of the computing carriage plus the distance through which the paper carriage travels. Between said plates 88 and 34 extend two tubes 89, 90, aligned end to end the outer ends of which are loosely mounted in sockets in said plates respectively. Within the tube 90 on the right extends a square computing shaft 91, which, at the right hand end, passes through the plate 34, and has secured thereon means, to be presently described, for rotating said shaft 91, and, at the left hand end, is formed with a ring 92 of the same diameter as the two tubes 89, 90, and lying between the inner end of said tubes, said shaft being also formed, at the sides of said ring, with circular, hub-like

portions 93, upon which the inner ends of the tubes are supported. Thus the square computing shaft rotates within the tube 90 on the right, and its hub on the extreme end thereof rotates within the tube 89 on the left. The tubes and shaft are not capable of any longitudinal movement, but the tubes are confined between the plates 88 and 34. Upon said tubes, and within the carriage, travel a series of computing wheels 95, Figs. 13, 15, and 16 each computing wheel being formed in the middle as an internal gear wheel, having ten recesses or notches 96, and the ring or hub 92 has, projecting therefrom, two diametrically opposite pins 97, Fig. 18 which are adapted to enter any diametrically opposite pair of the ten notches 96, and thus act as a master wheel to directly rotate that computing wheel only which is immediately over said ring. The tubes 89, 90, are preferably of such length, and so arranged, that the master wheel is at, or substantially in the same vertical plane as, the writing point of the typewriter. Each computing wheel is formed with external gear teeth 98 which mesh with gear teeth 99 formed at the side of a corresponding figure wheel 100, said wheels being all loosely mounted upon a hollow shaft 101 which extends between the end plates of the carriage. Therefore, if the computing shaft is rotated through any given angular distance, the figure wheel, which is immediately over, or in the same vertical plane as, said master wheel 92 on said computing shaft, is correspondingly rotated.

Horizontal or secondary computing mechanism.—The horizontal computing mechanism (Figs. 1, 11, 12, 14, 25^a, 25^b, 25^c) is, in general construction, similar to the main computing mechanism. The description, therefore, of such parts of the main computing mechanism as are also found in the horizontal computing mechanism applies also thereto, corresponding parts being indicated by the affix "x" for the horizontal computing mechanism.

Addition and subtraction.—The computing shafts, 91, 91^x, have respectively secured upon the ends projecting through the plate 34 bevel gears 103, 103^x, Figs. 1 and 19 which are adapted to be driven by a vertical shaft 104, having at the lower end a bevel gear 105, driven by a bevel gear 106 upon a horizontal shaft 107 having a bevel gear 108 driven by a bevel gear 109 upon the controller shaft. When said controller shaft has been released by the depression of the numeral key and rotates through an angular distance corresponding to the numeral key depressed, said rotation is transmitted to the vertical shaft 104 and thence to the shafts 91, 91^x, selectively in one or the other direction by means of sliding clutches 110, 110^x, slideable upon said vertical shaft 104 but rotat-

ing therewith. By means of a lever 111 the clutch 110 is adapted to be brought into operative engagement with either of two bevel gears 112^a, 112^b, loose on the shaft 104 and always in engagement with the bevel gear 103. If said lever is moved upwards, then the clutch 110 is moved into engagement with a clutch member formed within the upper bevel gear 112^a, thereby rotating the computing shaft 91 in the direction proper for addition. If said lever is moved downwards, the clutch 110 engages the clutch member of the lower bevel gear 112^b and rotates the shaft 91 oppositely to its former direction, causing the computing wheels to subtract. If said lever is moved to an intermediate position, the clutch 110 is out of engagement, and the computing shaft 91 does not rotate. In order to retain the lever 111 in any position to which it has been moved there is provided a loop 113, Figs. 19 and 25 secured to the front edge of the plate 34, having three notches 114 adapted to selectively receive the edge of the lever, the lever having sufficient lateral spring pressure to retain it in either notch. The numerals 112^a, 112^b, 111^a, 113^a, 114^a, indicate parts for the secondary mechanism corresponding to the parts 112^a, 112^b, 111, 113, 114, of the main mechanism.

Transfer mechanism.—The transfer mechanism is the same in the secondary computing device as in the primary computing mechanism, and I shall now describe the transfer mechanism of the secondary, referring to Figures 11, 12 and 14. Upon the left side of each computing wheel 95^x, near the periphery, is formed a single lug or pin 115^x, Fig. 17 and each time that said wheel makes a complete revolution, said pin engages one of five teeth of a transfer wheel 116^x, loose on a shaft 117^x, which wheel has formed, on the left hand side, gear teeth 118^x which mesh with the external gear teeth 98^x on the right hand side of the next computing wheel 95^x to the left. Thereby said wheel on the left is partly rotated through one-tenth of a revolution. Said transfer wheel 116^x has also formed thereon five concave sides 120^x each in an arc of a circle of slightly greater diameter than that of a transfer cylinder or roller 123^x, preferably of rubber or similar resilient material, and has a hollow square metallic core 122^x. There are a series of such rollers 123^x, all carried with the computing carriage, one between every two adjacent partitions, and through the cores 122^x, passes a square transfer shaft 121^x, which, as hereinafter described, constantly rotates, Figs. 1, 4, 11 and 22.

When, by the advance of the lug 115^x, in the manner just explained, the transfer wheel 116^x has been moved through a distance corresponding to a part of one-tenth

of a revolution of the computing wheel, it is then in such a position that one of its projecting portions 124^x, between two adjacent concave sides, has been forced into sufficiently close contact with the constantly rotating transfer roller 123^x and is rotated with the latter, until its next concave side, in turn, assumes a position over the rubber body of the transfer shaft without being in contact with it. 70 75

The corresponding parts of the primary computing mechanism, where they appear, are correspondingly numbered, but without the exponent. 80

The transfer shaft of the primary computing mechanism, at one end passes through the plate 34 and at the other end is supported by bearings in the partitions, and the end plate and partitions of the computing mechanism are cut away to pass the roller 123. The shaft 121 and roller 123 have no relative longitudinal movement, but have a constant rotary movement, which is derived from the electric motor, by means of a gear wheel 125 on the shaft of the motor, meshing with an idle gear wheel 126 which in turn meshes with a gear wheel 127 (Figs. 1, 19 and 20) on a shaft 107 carrying a bevel gear 106^x which meshes with a bevel gear 105^x on a vertical shaft 104^x with which co-operate parts similar in their general construction and arrangement to those immediately co-operating with the vertical shaft 104, except as to the form of the clutch sleeve 110, Fig. 22 which in this case only has a pair of teeth instead of a number thereof on each side the reason being that said shaft 104^x revolves constantly at a rapid speed, and, when the direction of computation is changed, this must be done while said shaft 104^x is in motion, whereas, with the computing shaft 91 the direction of motion is never changed except when the shaft 104^x is at rest. By arranging the clutch mechanism for the computing shaft and for the transfer shaft to be actuated by a common lever 111, it is insured that the transfer shaft will always be rotated in unison with the computing shaft. It will be seen that all of the computing devices contained in the main computing carriage are operatively connected throughout the entire series, so that the whole series can be used for a single column or for a variable number of independent columns. 100 105 110 115 120

The secondary mechanism is similar to that of the main in the relation of the computing wheels to the figure wheels, the general construction of the transfer shaft, and the clutch mechanism for shifting both the computing and transfer mechanism into any one or three positions to add, to subtract, or for throwing out of operation. 125

In order to align the figures on the figure wheels and to insure that the transfer wheel 130

is not unduly rotated, there is provided, similar mechanisms for the primary and secondary computing devices. Referring to Figures 11, 12 and 14, there is provided for each such transfer wheel, a pivoted detent arm 130* carrying a roller 129* (Fig. 36) which is pressed by a spring 131* into one of the concave sides of said transfer wheel. It will thus be seen that each computing wheel cannot be advanced by the transfer mechanism more than one-tenth of a revolution, first, because of the roller 129*, and second, because of the concavity of the sides of the transfer wheels, the points of which cannot take hold of the rubber roller 123* of the transfer shaft and rotate with it, unless positively forced thereinto.

Grouping.—The figure wheels are visibly spaced into groups of three, each group, together with the spacing means, occupying four writing spaces of the typewriter. The spacing is preferably effected by the partitions, one of which is interposed between each group and the next, as shown in Figure 13 and occupies the fourth writing space, or a portion thereof. If only a portion, the figure wheels should be made correspondingly wider, but always so that the sum of the widths of the three figure wheels, together with that of the spacing means, is equal to four writing spaces of the typewriter. Since the computing wheels are also divided into groups of three by the partition, the hub 136 of the computing wheel at the left of the group rotates in a recess 137 in the partition, said hub and the hole in the partition being of sufficient internal diameter to permit the master wheel to revolve freely therein, so as to have no effect on the computing mechanism, in case the computing shaft should be rotated at the time the operating point of the typewriter is at any fourth space of the computing mechanism.

This arrangement provides that, without disconnecting the numeral key levers from the computing mechanism, the machine is free to operate at each fourth writing space without affecting the computing wheels, so that this space can be used for pointing off the hundreds from the thousands, the thousands from the millions, and so on, and for separating the different columns thereby avoiding any derangement of the computing mechanism or error on the computation through erroneously striking a numeral key at that point.

In order to ascertain at any desired time the points at which computation is taking place, either in the main or in the horizontal computing mechanism, there are provided stationary or movable pointers 142 which are preferably in vertical alignment with the master wheel of the main computing shaft,

Resetting, and error correction.—The subtracting mechanism provides a convenient means for resetting to zero, either for a single figure wheel to correct an error, or for a series of figure wheels to begin a fresh computation. If, just before writing any total, either of vertical or of horizontal computation, the computing mechanism be reversed, then, at the time of so writing the total, the figure wheels giving such total will be thereby reset to zero.

Cross-totaling.—One object of the horizontal, or secondary, computing mechanism is to furnish a cross total of a row of figures in the several columns which are being computed by the main computing mechanism, as said figures are progressively written in said columns. But the principal value of this mechanism is its adaptability for the purpose of a billing machine, that is, a machine by which there is obtained a balance of one or more columns in which some items are to be subtracted, as well as others added, the machine being provided with means for obtaining a horizontal total of two or more rows, or a balance or difference of two numbers in a row, to write the total or difference in a separate column, and at the same time to reset to zero the horizontal computing mechanism in readiness for a similar operation while still retaining the result of each such independent operation in a separate column in the main computing mechanism. The main computing mechanism performs a selective computation of the vertical columns of numbers, while the secondary computing mechanism computes horizontally aligned numbers.

To accomplish this, the secondary computing mechanism, in the preferred form shown in Figures 1, 11, 25*, 25* and 25*, has its computing wheels held stationary while the master wheel or actuator 97* is arranged to move successively through them to engage with the internal gears thereof.

The computing wheels are supported in a frame 144 fixed to the frame of the machine and comprising end plates 145 and a casing 79* slotted at 81* to show the numbers therethrough. The computing shaft 91* has no longitudinal movement itself, but supports the master wheel 97* which is splined thereon, so as to rotate therewith and yet capable of sliding longitudinally thereof. A pair of tubes 90* are connected at their inner ends to the hub of the master wheel 97* so as to move the master wheel through the computing wheels. The other ends of said tubes are supported upon circular flanges 146 secured to extend inwards from the side plates 167 of a movable frame 148, said frame having also longitudinal rods 149, connecting said side plates and sliding through bearings 150 upon the end plate 130.

145 of the frame for the computing mechanism.

This frame 148 derives its movement in the following manner. Secured to said frame 148 is a rack 151 (Figs. 11 and 26) which engages a gear wheel 152 upon a vertical shaft 153 having fixed bearings 154. The front side of said gear wheel 152 meshes with a rack 155 attached to a connector rod 156 (Fig. 1) made in sections and connected by a turn buckle 157 (Fig. 36), so as to permit of longitudinal adjustment, the front end of said rod 156 sliding through a guideway 158 (Figs. 1, 26, 27 and 28) on a fixed bar 159. Said guideway is open on the under side, Fig. 11 and the rod 156 is resiliently supported in said guideway by means of a spring 160, secured as shown at 161 to said bar 159, the free end of said spring bearing upwards against said rod and holding it in place in the guideway. Upon the forward or advancing end of the rod 156 is formed or secured a catch 162 adapted to engage the lower edge of any one of a series of shifters 163, which are all of the same construction.

Each shifter is interchangeably supported upon a bar 164 which is secured at its ends to the main computing carriage 74 and moves therewith. This bar 164 has a series, spaced correspondingly with the writing spaces, of upper and lower transverse grooves 165, 166, (Figs. 1 and 26) and in the front side of said bar, intermediate between said grooves there are a corresponding series of threaded recesses 167. Each shifter comprises a cylindrical threaded body portion 168, Fig. 26 through which extends the stem of a screw 169 adapted to be screwed into any one of said threaded recesses 170 and having a head 171 by which it can be conveniently so screwed, and has also keys 172, 173, Fig. 11, adapted to selectively enter a pair of the aforesaid grooves. One key 172 of each shifter is comparatively narrow, and is convexly curved at its outer edge, while the other key 173 has an outwardly directed extension or lug 174, thereby rendering the key comparatively wide. When said shifter is placed upon the shifter bar so that the wide key 173 is uppermost, it is then in its inoperative position, but when so placed that the wide key extends downwards, then it is in an operative position. In either position any shifter may be very firmly secured upon the bar by screwing in the screw 169.

When any shifter is placed in its operative position, it acts in the following manner. The catch 162 has in its upper edge a recess 175 and said edge slopes downwardly on each side of said recess 175, the inclined portion 176 of said edge on the forward or advancing side of the recess rising higher than the inclined portion 177 on the rear

side. Supposing, then, that the lug 174 of a shifter is engaged in said recess 175, the effect will be that, as the main computing carriage advances, it draws with it the rack 155 through the medium of the shifter bar 164, the shifter 163 thereon, the catch 162, and the connector rod 156. It thereby turns the gear wheel 152, and causes the rear rack 151 to correspondingly move in the opposite direction to the main carriage. Thereby the tubes 90* supported within the frame 148 move to the right, carrying with them the sleeve 92* having the pins or master wheel 97*. Therefore, for each movement to the left through a typewriting space of the main computing carriage, the operating pins 97* move through the secondary computing wheels a corresponding distance to the right, and are thereby moved into operative connection with the next computing wheel on the right. In this manner, for every computation made upon a main computing wheel, a corresponding computation is made upon a secondary computing wheel, either of addition or of subtraction.

The shifters are first arranged in any number and variety of position in accordance with the position of the columns which are to be written by the typewriting machine and of which it is desired to obtain the horizontal computation. Having so arranged the shifters upon the shifter bar, when the main computing carriage arrives at the first column, then a lower oblique surface 178 formed in the catch 162 engages a stop 179 secured upon the bar 159, and depresses said catch, so that it is moved away from the depending lug 174, and its recess 175 is freed from said lug. Then the rod 156 and rack 155 immediately return under the action of a spring 180 enclosed in a spring case within the gear wheel 152. This has the effect of returning the movable frame 148 and the operating pins 97* to their normal positions, unless intercepted and arrested by a succeeding shifter, which takes place in the following manner.

As the rack 155, and the connector rod 156 attached thereto, return under the action of the spring 180, Fig. 11 the sloping surface 177 on the rear side of the recess 175 in the upper edge of the catch 162 engages the lower edge of the lug 174 depending from the next operative shifter to the right, so that said catch is thereby depressed against the action of the spring 160, until the recess 175 arrives immediately below said depending lug, and the front, or left hand, edge of said recess strikes the side of said lug 174, it being with this object that the sloping surface 176 on the left side is made somewhat higher than that, 177, on the right side. The abutment of said side of the recess against said lug immediately arrests the return movement of the rack and

connector rod, and the catch 162 is immediately moved upwards by the action of the spring 160, so that the lug 174 of said operative shifter to the right, now, in turn, 5 engages said catch in the same manner as it was engaged by the next operative shifter to the left, as previously described. The actuation of the secondary computing mechanism, in unison with the main computing mechanism is now repeated for that portion of the main computing mechanism which has the proper relative location to said second shifter that has come into action. Supposing that the secondary computing mechanism has been set for the operation of addition, the effect of causing the same to be actuated, first, in unison with the number wheels for the first column and then again in unison with the number wheels for the 10 second column, will be to add these numbers on the secondary computing mechanism, so that the figures displayed by the secondary computing mechanism will indicate the sum of two figures in the same row of the two 15 columns.

In precisely the same manner, when the second column has been completely written, the catch is automatically disengaged from said second operative shifter, and returns 20 until it is caught and engaged by the next shifter which is operatively arranged. Or, it may move back its complete distance, and be subsequently engaged and carried forward by the next operative shifter on the 25 right on the arrival of the latter at the catch 162. In either case, if the secondary computing mechanism is still set for the operation of addition, the figures displayed thereby will show the sum of the numbers, 30 in the same row, of three columns. This operation may be continued for all the columns capable of being written on the sheet.

On the other hand, if, after writing the 45 first column, or any number of columns, the secondary computing mechanism is set to perform the operation of subtraction, then, upon writing the next succeeding column, the number of any row in that 50 column will be subtracted from the sum of the numbers of the column or columns preceding, and the figures displayed by the secondary computing mechanism will show the difference, or balance, after deducting 55 the amount which it is desired to subtract.

It will be readily understood that the operation of adding or subtracting numbers in a row, which is effected by the secondary computing mechanism, does not in any way 60 affect the addition or subtraction which is independently effected of the numbers in any one or more columns by the main computing mechanism, so that, while the totals of the several columns are independently 65 registered by the main computing mecha-

nism, the cross totals, or differences, of the numbers in the same respective columns, are registered by the secondary computing mechanism.

When the operator returns the paper carriage to the right to begin a new line, all of the depending lugs 174 of the shifters which are operatively arranged impinge in succession against the sloping advancing portion 176 of the upper edge of the catch, and thereby depress said catch and readily pass over the recess 175 by reason of the greater height of said advancing sloping portion 176 than that of the rear sloping portion 177 so that no obstruction is offered to the movement of the carriage to the right.

In the modification shown in Figure 30, the gear wheel 152, instead of being horizontal, is vertical, the shaft for said wheel being suitably mounted on the frame of the machine, the bar 159, and the shifter mechanism generally being then arranged somewhat higher than in the form of the mechanism first shown. In other respects the construction is the same as in the preferred form. In Figure 30 the reference numerals correspond with the views showing the preferred form but have the exponent "f."

In the modification shown in Figure 31, instead of the same gear wheel engaging both racks, a small gear wheel 210 may be used to engage the upper rack, and a large gear wheel 181, on the same shaft as the small gear wheel, may be used to engage the lower rack. In this case the distance through which the operating pins of the secondary computing mechanism moves is greater than the corresponding distance through which the carriage of the typewriter moves. This enables wider computing wheels to be used in the secondary computing mechanism, so that larger figure may be displayed thereon. In this view the other parts are numbered with the exponent "g" to correspond with the preferred form.

In the modification shown in Figure 32, the operating pins are stationary, and the secondary computing mechanism is contained within a carriage 183 which is attached to the connector rod by means of a slightly flexible connection and moves with the connector rod. In order to return said carriage when the catch is released, there is provided, on the under side of the same, a rack 184 engaged by a gear wheel 185 around a spring case 186, said gear wheel being mounted on a shaft 187 stationarily supported on the machine. In this view the other parts are numbered as in the preferred form, but with the exponent "h."

In the modification shown in Figure 33, in addition to moving the operating pins of the secondary computing mechanism, in the manner already described, the secondary computing mechanism is now itself movable,

and instead of a stationary frame for said mechanism I provide a carriage 188 which slides upon guides 189 and is moved with the main computing carriage in the same direction and with the same speed. This is accomplished by connecting said carriage 188 direct with the connector rod 156, the rack 185 being now attached to the carriage 188, the effect of which is the same as attaching it direct to the connector rod 156, so that the operating pins are moved as fast to the right as before, and at the same time the carriage of the secondary computing mechanism is moved with the same speed to the left, the result being that the operating pins move relatively to the carriage a distance twice that in the first form of the invention. This enables the computing wheels to be made twice as wide as before, so that the figures thereon can be made correspondingly larger. In this view the other parts are numbered as in the preferred form but with the exponent "m."

In Figures 34 to 38 I illustrate the preferred form of my invention in which while using the same key connections, the same controller, the same driving mechanism and transfer mechanism, and the same computing device, these devices are stationary, and the operating pins of both the main and secondary computing devices move through said devices. In these figures the unmodified parts are numbered as in the preferred form but with the exponent "n."

In this form of the invention, there is provided an upper rack 190 which moves with the paper carriage, and is preferably secured thereto, and which engages a vertical gear wheel 191, which is located substantially opposite to the writing point, or at the center of the machine, and the lower side of which engages a rack 192 which consequently moves to the right as the paper carriage moves to the left, and at the same speed. Said lower rack moves upon a slide-way 193 secured on the front of the machine and forms the upper part of a frame or carriage, comprising said rack 192; a shifter bar 164 forming the lower longitudinal bar of said frame or carriage, and constructed precisely like the shifter bar in the first form of the invention; a right hand end bar or plate 194 which is angular in form, so as to pass in front of the casing of the computing mechanism, and a left hand end bar or plate 195. Through the end plate 194 passes loosely the square computing shaft which is driven from the right in precisely the same manner as before and has no longitudinal movement. On said computing shaft is a sleeve 196 having a square longitudinal aperture therethrough to fit closely around said computing shaft, so that it can slide thereon, but turn therewith, said sleeve having at its left hand end the flange 197. In assem-

bling the parts this sleeve is inserted into the interior of a tube 198 and is moved therealong over the square computing shaft until said flange abuts against an inwardly extending flange 199 formed upon the inner 70 edge of said tube. The outer or left hand end of said tube 198 is formed with an outwardly extending flange 200 by means of which it is held by means of a disk 201 having a central aperture surrounding said tube 75 over said flange 200, said disk being secured to said end plate 195 of the carriage. Over said sleeve 196 is now passed a sleeve 202 carrying the operating pins 97. After said sleeve 202 and the inner sleeve 196 have been 80 placed so that they abut against the inwardly extending flange 199 they are secured together as by a pin 203. By means of this construction the operating pins 97 are arranged to be always at the same distance 85 from the end of the operating carriage while capable of rotation with the computing shaft.

When the typewriter carriage is at its initial position, to the extreme right of the writing point of the typewriter, then the operating pins are at the extreme left and in engagement with the first computing wheels which are then centrally located. As the paper carriage moves to the left, said operating pins move to the right in succession through said computing wheels, which are now stationary, and operate upon the said wheels in precisely the same manner as described in the first form of the invention, the only difference being that the operating pins are now movable, and the computing wheels stationary, instead of the computing wheels movable and the operating pins stationary. In this modification however the computation is not effected at the writing point of the typewriter, but proceeds from the writing point to the right at the same rate at which the writing is written, so that the computation is always at the same distance 100 from the beginning of the line of computations, as the part written is from the beginning of the line of writing.

The computing wheels which are not in use, that is, those to the right of the operating pins, are supported partly by the transfer wheels, and partly by idle gear wheels 206 upon a shaft 207 employed especially for the purpose of supporting these wheels in position. After the operating pins have 110 passed through the computing wheels they are then supported upon the tube 198.

The construction of the secondary mechanism is in general the same as that in the first form of the invention, except that no 125 rack is employed to connect the connector rod with the sliding frame carrying the operating pins, but said connecting rod is now connected directly to said frame, and moves in the same direction therewith. Conse- 130

quently said connector rod, instead of being pulled by the shifter bar and shifters, as in the first form of the invention, is now pushed thereby, and the arrangement of the 57 catch and the other parts of the tripping mechanism is now reversed, as to the longitudinal direction of the machine. That is to say, the advancing surface of the catch is now to the right instead of to the left. The 10 trip is also to the right of the catch instead of to the left, and similarly for other parts of the mechanism, as will be readily understood.

One advantage of this form of the invention is that it can be used with such machines as the Remington, in which the paper carriage is lifted to enable the typewritten matter to be inspected. In that case the upper rack 190 is lifted with the paper carriage and re-engages the gear wheel 191 when the carriage is returned to its normal position. Another advantage of this construction is that it enables the mechanism to be placed upon such machines as the 25 Oliver, in which the paper carriage moves through the center of the mechanism of the machine.

Uses of secondary computing mechanism.

The main purpose of the horizontal, or secondary, computing mechanism is to provide 30 means for obtaining horizontal computations of the amounts written in several independent and distinct columns, the main computing mechanism being for the purpose of 35 taking vertical computations. The computation of all columns, written at any points of the paper, from the extreme right of the same, will appear in the computing mechanism directly opposite to, or in front of, the 40 written figures themselves, as the computing carriage moves with the paper carriage, and in the same direction, and each computing device in the main carriage can be used only when the typewriter is writing in the 45 writing space occupied by that particular computing device, as indicated by the writing scale.

For instance, whenever a character is 50 printed by the typewriter when the paper carriage is located on the 15th. writing space of the typewriter, which is located $1\frac{1}{2}$ inches from the first writing space said character will always be exactly the same distance from the first possible writing point of the 55 typewriter to the left. The same holds with any other writing space of the typewriter. On all typewriters, so that the operator may know just at what point on the paper he is to write, there is provided a writing space 60 scale, such scale having as many divisions on it as the typewriter has writing spaces; hence the ordinary machine can write 80 characters to the line, when used to its writing limit, but, as the writing point is always 65 central, it can write in the 80th. space only

when the paper carriage has travelled to the left far enough to bring the 80th. writing space of the paper carriage into a central position, namely, the writing point.

Exactly the same principle is carried out 70 in connection with the main computing mechanism. The computing carriage is preferably made of the same length as the paper carriage, whatever may be the length of the latter or so as to contain computing devices coextensive with the writing spaces on the typewriter, one computing device being provided for each writing space, except in each fourth typewriting space, in which the computing mechanism is rendered inoperative, for the purpose of providing 75 means for pointing off the hundreds from the thousands, the thousands from the millions, the millions from the billions, dollars from cents, etc., whereby, when writing numbers of large denominations, the eye can read at a glance the number. Thus 876,876,876,876, or 1,000,000 or again \$678,876,88 is read at a glance, whereas if it were written thus:— 876876876876, or 1000000 or 678876,88 it 80 could not be read at a glance with any assurance of accuracy. This visible spacing, carried all through the mechanism together with corresponding spacing in the typewriting of the figures makes it very easy to read 85 numbers or amounts of any denomination or capacity at a glance, without any hesitancy, or possibility of making an error in the amount.

Further, this construction when placed 90 upon the ordinary typewriter, affords 20 distinct and independent computing mechanisms each of three figures, and each spaced from the nearest possible column by a full typewriter writing space, or one complete 100 computing mechanism capable of taking a column of a width equal to the numerical capacity of the entire machine. As all these 105 series of computing devices are operatively connected through this fourth inoperative computing space, it will be readily understood 110 that it is possible to take either 20 distinct and independent visibly spaced columns of a capacity of 999 each, or a smaller 115 number, of larger columns, with a capacity of 6, 9, 12, or more figures. In fact, with the mechanism herein shown, it is possible to compute a column of figures of the numerical capacity of the entire writing line, just as easily and as readily as to compute an 120 independent column of three or more figures. By this is meant that, if the whole 125 series of computing devices, as herein described, three for every four writing spaces, or sixty in all for the full 80 writing spaces, stood at zero, and the subtracting mechanism were thrown into operation, and the figure "1" struck on the typewriter, when the writing carriage was standing in the 130 80th. writing space, and the computing

mechanism therefor, which represents that figures written in 20 separate and independent columns, as they were written by the particular writing space, and can be operated, then the typewriter, in the travel of the paper carried at no other point, is operated, then the entire series, of 60 computing wheels, in range from right to left in its regular course across the writing point of the machine. 70

6 the main computing mechanism would instantly move one tenth of a revolution and would all stand and show upon their face the figures 9. If the computing mechanism were then changed to addition, and "1" was 10 written in the same 80th writing space, the whole series of 60 computing wheels would instantaneously be operated, and all would show zero. 15

With this explanation it will be readily seen that the main computing carriage is so constructed as to enable it to do a great variety of work, from the fact that practically every writing space of the paper can be used, and columns can be put as closely together as desired, without loss of space, or the necessity of providing unnecessarily wide margins between the different columns. 20

Now, if the horizontal or secondary computing mechanism were not made to fulfill the same conditions, the capacity or variability of the machine would be greatly contracted. For instance, the secondary computing mechanism must be capable, when desired, of taking a very large amount, or 30 very large numbers, such as millions or billions. It must therefore have nine or more computing mechanisms, which, with three for each four writing spaces, means that it must be 12 to 16 writing spaces in 35 length. Therefore, unless means are provided for accomplishing this without at the same time occupying 12 to 16 typewriter writing spaces for each independent column, the efficiency of the main computing carriage 40 will be reduced from 20 distinct columns to 5, 6, or 7, columns, even though the amount, or the numerical capacity, of such columns, were limited to 999, or less. It is to avoid this result that I provide the hereinbefore described means, whereby the secondary computing mechanism is made as variable in this particular, and even more so, than the main computing mechanism was enabled to be, by having a computing device 45 for each writing space, and divisions into groups of three. This is done by means of the above described series of shifters, which shifters can be placed as near to each other as desired, since at each writing space there is provided means for their attachment. It is the distance from one shifter to the next by which the size of the column following the second shifter is limited and this also determines the number of writing spaces on the paper between the figures of said column. 55

It will therefore readily be seen that, by placing one of these shifters in each fourth writing space of the typewriter, the secondary computing mechanism would compute 60 or add the horizontal or cross total of all

It will be seen that, if this can be done, it is also possible to take 10 columns with a capacity each of 999,999, or several columns with a capacity of six figures, and a number of other columns limited to three figures each. So it would be possible to have several columns with a capacity of 999,999,999, or even more, while still other columns could be limited to three figures or four typewriter writing spaces, others to six or less, others to nine or less, others to twelve or less, and others to even greater numerical capacity, without affecting in the least the writing space required or margin necessary for the smallest column. 65

Cross and grand total column.—Of course it would be useless to take horizontal or cross computations unless it were also possible to retain each one in a cross total column, and thus obtain the grand total by using the last column to the right as the cross and grand total column, writing only such amounts in that column as are registered by the secondary computing mechanism, after all the different amounts have been written in the respective columns of which it is desired to obtain a cross or horizontal computation. Before these numbers are written in said grand total column, the secondary or horizontal mechanism is shifted for subtraction, so that, when the numbers are written in this last column, the computing devices of this secondary mechanism are thereby brought to zero. But the numbers written in this 105 column, or cross total column, will also be registered in that portion of the main computing mechanism represented by the particular typewriter writing spaces in

which the column is located. It will readily be seen that this cross or grand total column need not necessarily be located at the extreme end of the writing line, or be computed by the computing devices at the extreme end or right of the main computing mechanism, but can be placed close to the end of the written line, or as far off as desired, according to the wish or fancy of the operator; or it may be placed in the middle, with debits on one side and credits on the other. 110

It will be seen, therefore, that the grand total of all vertical columns will always show on the computing mechanism, the instant each line of cross or horizontal computations is completed and the amount or total written in the cross, or grand total column. It will also be understood that the total of each vertical column will always show in the main computing mechanism 115 or add the horizontal or cross total of all 120

directly opposite to or in front of, the written column itself.

- Another feature of great value is the fact that both the main and the horizontal or secondary computing mechanisms are capable of being used for subtraction as well as addition, by reversing the operating mechanism. Or either the main or the secondary mechanism can be used independently of the other. The main can be used either for addition or subtraction, while the secondary is made inoperative, and the horizontal or secondary can be operated either to perform addition or subtraction, while the main is made inoperative, or either the main or secondary mechanisms can be made to perform addition, while at the same time the other mechanism is subtracting. Therefore either or both can be made to subtract or add at will, singly or together, or one to add while the other is subtracting, or vice versa, or both can be rendered inoperative, so that the typewriter can be used independently.
- It will have been seen that the main computing mechanism is adding, and at the time the secondary mechanism is subtracting, when each cross or horizontal computation is being written in the cross or grand total column. Now, when all the vertical and cross totals have been completed, and it is desired to write at the foot of each column the total of each column, then the main computing mechanism is caused to subtract, while the secondary or horizontal mechanism is caused to add, the result of which is that, as the total of the first vertical column, as shown in the main computing mechanism, is written at the bottom of that column, the computing devices in the main computing mechanism are brought back to zero, while at the same time, the amount written, as the total of said column, will be shown upon the computing devices of the horizontal or secondary computing mechanism. Then, as the total of the second vertical column is written at the bottom of said second column, the computing devices of the main mechanism representing this column will be brought to zero, and the total of that second column will be added to the numbers already recorded in the horizontal or secondary mechanism, and so on with the third, fourth, fifth or any number of such vertical columns. After the totals of all vertical columns have been written at the bottom of each of the independent columns, the computing devices of the horizontal or secondary computing mechanism will show exactly the same figures as, or, in other words, tally with, those of the vertical total of the cross total column, as shown upon the computing devices of the main computing mechanism opposite to said cross or grand total column. Before the grand total is written at the foot of the cross or grand total column, the sec-
- ondary computing mechanism is also shifted for subtraction, and the writing of the grand total at the bottom of the grand or cross total column will then return the computing devices of the horizontal or secondary mechanism to zero, as well as the computing devices representing such column in the main computing mechanism, so that both the main and secondary computing mechanism will be all at zero, ready for another series of computations.
- This method of bringing these mechanisms to zero, has many advantages other than the fact that it clears the computing mechanism so that it is always ready for operation.
- It acts as a check upon the accuracy of the machine, since the same total must be obtained through the operations of two different mechanisms.
- Further, it makes errors in transcribing the cross total in the cross or grand total column impossible without detection, as, when subtracting the amount from the horizontal or secondary mechanism, if the numbers are copied incorrectly, the mechanism will show it, since the device or devices in which the error has been made will not return to zero, but will indicate in which figure the error occurred, and the extent of that error, which without losing the computation can be easily corrected in the following manner: If the figure to be written was "9" and a "6" had been written instead, both mechanisms should first be reversed to the opposite of what was previously done; the figure "6" should then be written; this would be the means of restoring each mechanism to its correct and normal condition with regard to this particular figure; this wrong figure, the "6", should then be erased from the paper; when this is done the mechanisms should then both be brought to their previous functions, of addition or subtraction; the proper figure "9" is then written in its proper place, and the error has now been corrected, and the proper computation retained and properly recorded in the cross or grand total column. This operation is also performed when the totals of all vertical columns are written at the bottom of their respective columns. Should any error be made in recording or writing the total of a vertical column, the computing devices representing this particular total or computation will not be returned to zero, but will show the error, which can be remedied and taken out in the same manner, as above described. It will therefore be seen that the machine is a check upon the operator, as well as one part of the computing mechanism being a check upon the other as above described.

Another valuable object, if not the main object, of the horizontal or secondary computing mechanism, is its adaptability, when

used alone, and independently of the main computing mechanism, for ordinary billing, or for the purpose of procuring the balance of two or more columns where debits and credits are used in the same or in separate columns.

Of course, for ordinary bill work, not more than one vertical column would be required, but it is customary to have the total of the amounts charged in a bill, written to the right of the column itself. If this is done, and the main computing mechanism used, the total of the column would still show on the computing devices opposite to the column, and also in the computing devices opposite the writing spaces where the total was written, in case they were not thrown out of operation before doing so. But, with the use of the horizontal or secondary computing mechanism, as already shown, the total of its additions, or computations, can be written at any point on the paper, and the computing mechanism through such operation returned to zero, whether such total is written to the right or to the left of one, two or more vertical columns. The advantages of this feature will be more fully understood by the following example.

	Debit.	Credit.
Balance on deposit January 1.....	61,345.67	
Received for deposit Jan. 2.....	6,432.56	
Check payable to J. Stevens Jan. 1.....		10,000.00
Check payable to John Morgan.....		432.23
Draft payable J. S. Pickson.....		3,345.23
Balance, cash on hand-Jan. 2.....	47,000.77	

As all typewriters are now generally equipped with parti-colored ribbons, the credit column and all deductions should be in red, thus plainly indicating the fact that said column is a credit, withdrawal, or discount column. It will also be readily understood that with this mechanism, and a parti-colored ribbon, one column could be used as readily as two or more and still contain the same result, the debits being written in the same vertical column with the credits, the credits being in red and the debits in black, or in other suitable colors of contrast sufficient to designate their difference.

The above example could be written as follows:—

54,345.67	
6,432.56	
	10,000.00
	432.23
	3,345.23
	47,000.77

and the result of copying the total, or the balance, of the computation by the secondary mechanism, would have been the same,

as by such copying, if arranged to subtract, the mechanism would be emptied, or returned to zero, ready for the next series of computations.

Attention is called to the fact that, when using the secondary mechanism alone, it is not limited in its capacity, but can be operated at any writing space desired, and for any number of different and independent columns, some of additions, and others containing only subtractions, and still obtain the balance total. Of course when used upon this work, independently of the main computing mechanism, the independent totals of each of the vertical columns are not obtained, but only the grand total; or the balance, of the figures written in one or more columns. This mechanism is all that is required for ordinary billing; or for billing showing discounts, with a separate discount column if desired. The main mechanism would not usually be required for this work, that being used more for statistical work, bookkeeping, clearing house work, etc., whereas this secondary mechanism when used alone, is usually all that is required for ordinary bill or statement work. Itemized statements of accounts, showing all charges and all credits, can be shown either in the same column in different colors, or in separate columns in the same or in different colors, for debits and credits; and the balance can be shown at the foot of either the debit or the credit column, or to the right or left of either with the same result as though written at the bottom of either.

Shift mechanism.—As a modification of the shift mechanism, the device for throwing in and out the numeral keys for computing may be attached directly to the shifting part of the typewriter, instead of to the shift key lever, whether used to shift the platen or to shift the type basket. The advantage of this construction is that the numeral keys are thrown out of operation when the shifting mechanism is used on either side of the typewriter, either by the unlocked shift key, which returns immediately upon the removal of the finger, or by the locked key, which stays depressed until it is released. For instance, the attachment may be by means of a hanger bar attached to the typewriter basket in the Monarch machine, the bottom of which bar is connected to a bell crank lever, the other end of which operatively engages the horizontal slide bar 5, which throws the numeral keys into operation. A spring normally returns the slide bars 5 into the position that the hooks 12 engage the collars 14, so that the numeral keys are operative for computing. The rise of the type writer basket in the Monarch, or the rise of the platen in the Underwood or other machines of that character, shifts said slide bar, against the

action of said spring, to release said hanger hooks.

5 *Automatic reversal.*—If desired it may be provided that the subtracting mechanism is automatically thrown into action when a red ink ribbon is used. This may be done by connecting the lever which controls the reversal to the horizontal arm of a bell crank lever, the vertical arm of which is connected by a horizontal crank to the mechanism which shifts from red to black, so that when the latter link is moved longitudinally the reversing device is moved vertically.

15 I claim:

1. In a computing attachment for typewriters, the combination of computing means, a source of power therefor, an operative connection between said source of power 20 and computing means, comprising friction surfaces, springs rubbing thereupon, and manually adjustable means in connection with said springs for regulating the amount of friction between said springs and said 25 surfaces, substantially as described.

2. In a computing attachment for typewriters, the combination of a paper carriage, computing mechanism, means for actuating said computing mechanism, means for connecting the same with the paper carriage, means for automatically releasing the same as the carriage advances, and means for varying the point of attachment of said connection, comprising a shifter, a bar, and 35 means for locking the shifter to said bar, substantially as described.

3. In a computing attachment for typewriters, the combination of a paper carriage, computing mechanism, means for actuating said computing mechanism, means for connecting the same with the paper carriage, and means for varying the point of attachment of said connection, comprising a shifter, a shifter bar provided with means 40 corresponding to the several writing spaces for attaching the shifter thereto, and means for securing the shifter thereon at any one of said spaces, substantially as described.

4. In a computing attachment for typewriters, the combination of a paper carriage, computing mechanism, means for actuating said computing mechanism, means for connecting the same with the paper carriage, and means for varying the point of attachment of said connection, comprising a shifter bar, and a part attached thereto, means attached to said computing device and arranged to be automatically engaged by said part, and means for automatically releasing it from said part, substantially as described.

5. In a computing attachment for typewriters, the combination of computing mechanism, means for actuating said computing mechanism, a paper carriage; means for con-

necting the same with the paper carriage, and means for varying the point of attachment of said connection, comprising a shifter bar, and a part attached thereto, means attached to said computing device and arranged to be automatically engaged by said part, at a variable point on the shifter bar, and means for automatically releasing it from said part, at a fixed point, substantially as described.

6. The combination of a computing device, a paper carriage, a connector bar, a plurality of shifters movable with the paper carriage, means for connecting the connector bar with said shifters in succession, means for withdrawing the connector bar at a definite point in its advance with the shifter, and means whereby the shifters can freely return past the connector bar when the carriage returns, substantially as described.

7. The combination with computing mechanism, of a shaft extending through said computing mechanism, an actuator for said computing mechanism, splined on said shaft so as to be rotatable therewith and yet capable of sliding longitudinally thereof, and a tube circumjacent said shaft and connected to said actuator to move the same through said computing mechanism.

8. The combination of a carriage, computing mechanism, an actuator for said computing mechanism, movable therewithin, a shaft, means for rotating said shaft, said actuator being movable along said shaft, but rotating therewith, and means operated by the movement of the carriage, for moving said actuator, substantially as described.

9. The combination of a paper carriage, computing mechanism, an actuator for said computing mechanism movable therewithin, a shaft, means for rotating said shaft, said actuator being movable along said shaft, but rotating therewith, and means operated by the movement of the paper carriage, for moving said actuator, substantially as described.

10. The combination of computing mechanism, an actuator for said computing mechanism, movable therewithin, a shaft, means for rotating said shaft, said actuator being movable along said shaft, but rotating therewith, a tube adapted to move within the computing mechanism and connected to said actuator to move it longitudinally, and means for moving said tube, substantially as described.

11. The combination of a paper carriage, computing mechanism, an actuator for said computing mechanism movable therewithin, a shaft, means for rotating said shaft, said actuator being movable along said shaft, but rotating therewith, a tube adapted to move within the computing mechanism and connected to said actuator to move it longi-

itudinally, and, means whereby the movement of the paper carriage moves said tube, whereby they move in opposite directions, and means carried by said frame and rotatable with the computing shaft for actuating said computing shaft in succession as the frame moves, substantially as described.

12. The combination of a paper carriage, computing mechanism having a computing wheel corresponding to each typewriter space of the paper carriage, a device adapted to pass through said computing mechanism in the opposite direction to the paper carriage, and operatively connected therewith, a stationary shaft for operating said device, and means for rotating said shaft by the depression of a numeral key, substantially as described.

13. The combination of a paper carriage, computing mechanism having a computing wheel, corresponding to each typewriter space of the paper carriage, a device adapted to pass through said computing mechanism in the opposite direction to the paper carriage, and operatively connected therewith, a stationary shaft for operating said device, a tube around the shaft, and arranged to move within the computing wheels, and means for rotating said shaft by the depression of a numeral key, substantially as described.

14. The combination of a paper carriage, computing mechanism having a computing wheel corresponding to each typewriter space of the paper carriage, a device adapted to pass through said computing mechanism in the opposite direction to the paper carriage, and operatively connected therewith, a stationary shaft for operating said device, a tube around the shaft and arranged to move within the computing wheels, means for supporting said computing wheels independently of said tube, and means for rotating said shaft by the depression of a numeral key, substantially as described.

15. In combination with numeral keys, stationary computing mechanism, a stationary shaft, means for rotating said shaft by the operation of the numeral keys, and an interior operating device movable on said shaft through said computing mechanism and rotating with said shaft, substantially as described.

16. In combination with numeral keys, stationary computing mechanism, a stationary shaft, means for rotating said shaft by the operation of the numeral keys, an operating device movable on said shaft through said computing mechanism and rotating with said shaft, and means arranged around said shaft behind said device to maintain said mechanism out of contact with said shaft, substantially as described.

17. In combination with computing mechanism, a longitudinally moving frame of substantially the same length as said computing mechanism, a stationary computing shaft, a paper carriage, a connection between

said paper carriage and frame, whereby they move in opposite directions, and means carried by said frame and rotatable with the computing shaft for actuating said computing shaft in succession as the frame moves, substantially as described.

18. The combination with a movable typewriter carriage, of a stationary computing mechanism free from movement with said carriage, an actuator for said computing mechanism, and means for enabling a continuous movement of said carriage in one direction to produce an intermittent reciprocating movement of said actuator, said carriage moving said actuator in a direction opposite to its own movement.

19. The combination of a paper carriage, a stationary computing device, an actuator therefor moved by the paper carriage in the opposite direction thereto, and automatic means for operatively connecting said actuator to said carriage at predetermined points in the path of the latter, substantially as described.

20. The combination of a typewriter carriage, computing mechanism, an actuator therefor, a device movable by the typewriter carriage, means carried by said device for moving one of said elements, said mechanism and actuator, with the typewriter carriage, means for disconnecting said last-mentioned means, means for automatically reversing said movement, and means for varying the extent of said reverse movement, substantially as described.

21. The combination of a typewriter carriage, stationary computing mechanism, an actuator therefor, a device movable by the typewriter carriage, means carried by said device for moving said actuator with the typewriter carriage, means for disconnecting said last-mentioned means, means for automatically reversing said movement, and means for varying the extent of said reverse movement, substantially as described.

22. The combination of a typewriter carriage, calculating mechanism comprising two primary elements, a computing device and an actuator therefor, means for advancing one of said elements relatively to the other, means for operatively connecting said advancing means with the typewriter carriage, whereby they move in unison, means for breaking said connection at a constant point in said advance, means for moving said element in the reverse direction when said connection is so broken, and means for varying the extent of said return movement, substantially as described.

23. The combination of a typewriter carriage, calculating means comprising two elements, a computing mechanism and an actuator therefor, a device movable by the typewriter carriage, means carried by said

- device for moving one of said elements with the carriage, means for arresting said movement, means for automatically causing reverse movement, and means selectively located to correspond with predetermined writing spaces for limiting the extent of the reverse movement, substantially as described. 6
24. The combination of a typewriter carriage, a stationary computing mechanism, an actuator therefor, a device movable by the typewriter carriage, means carried by said device for moving said actuator with said carriage, means for arresting said movement, means for automatically causing a reverse movement and means selectively located to correspond with predetermined writing spaces of the typewriter for limiting the extent of the reverse movement, substantially as described. 10
25. The combination of a paper carriage, a main computing mechanism comprising a computing device and an actuator therefor, one of said elements of the computing mechanism being movable with the paper carriage, a secondary computing mechanism comprising a computing device and an actuator therefor, means for connecting one of the latter elements with the movable element of the main computing mechanism, means for automatically disconnecting said elements, and means whereby either actuator may be operated independently of the other, substantially as described. 15
26. The combination with a succession of computing wheels, of a tens-carrying device controlled by one wheel to effect advance of the next higher wheel, and a constantly rotating member to engage said tens-carrying device and actuate the same, each tens-carrying device being rotatable by the wheel of lower denomination, and being forced into engagement with the constantly rotated member to be rotated thereby, the tens-carrying device having teeth to engage said rotating member, the latter having a yielding construction and gripping each tooth to turn the tens-carrying device, the computing wheels being divided into groups of three, and a series of soft rubber cylinders being mounted at corresponding intervals along the rotating shaft. 20
27. The combination of computing wheels with a step-by-step moving carriage to carry the computing wheels, a non-traveling power-rotated shaft 121, and the constantly rotating device 123 traveling with said carriage and splined upon said shaft. 25
28. The combination of a gross computing mechanism a single row of primary computing wheels divided into sections of three wheels each, the sections spaced each from the next, to permit computing any desired number of primary columns written closely side by side, and to permit any desired number of 65
- columns written closely side by side, and to permit any desired number of wheels to be reserved for each column at any place in the row, and also having means for automatically effecting the resetting of the gross computing mechanism for each of the primary columns during the writing of each line, regardless of the respective widths of the several primary columns or the distance at which one column is spaced from the next. 70
29. The combination of lugs (174) connected at intervals to the traveling carriage of the typewriting machine, to be engaged successively by a catch (162) connected to the traveling member or members (98*) of the gross computing mechanism, to enable the typewriter carriage to advance said traveling member step-by-step; an interceptor (179) being provided to trip or disconnect the catch (162) from each lug (174) to be engaged by the succeeding lug, a spring 75 being provided to retract said traveling member of the gross adding mechanism, each lug (174) determining the point at which the next computation is to begin, the lugs (174) being adjustably mounted upon a rack (164). 80
30. In combination with primary computing mechanisms including primary computing wheels arranged in column groups for adding numbers written in each of a plurality of primary columns, so as to produce the footing (or total) of each individual column separately from the others, of secondary computing mechanism including secondary computing wheels for simultaneously computing the gross amount (or cross footing) of all the numbers written in the several columns, respectively, of each line across the page, a gross master wheel (97*) to actuate said secondary computing mechanism, a primary master wheel (97) for actuating said primary computing mechanism, and means for effecting repeated relative reciprocations between said gross master wheel and said gross computing wheels during a single complete relative movement or progress in one direction, between the single primary master wheel and all of the several column groups of primary computing wheels, the said secondary computing device being arranged to either add or subtract, whereby any of the respective amounts written in the primary columns may be either added or subtracted by the secondary computing device, at the will 100 of the operator. 105
31. The combination of a single row of primary computing wheels divided into sections of three wheels each, the said sections being spaced each from the next to permit computing any desired number in primary columns written closely side by side, and to permit any desired number of 110
- 115
- 120
- 125

wheels to be reserved for each column at any place in the row, gross computing mechanism for summing up the primary columns horizontally during the writing 5 of each line, and means for automatically effecting the resetting of the gross computing mechanism regardless of the respective widths of the several primary columns, or the distance at which one column is spaced 10 from the next, the said gross computing device being arranged to either add or subtract, whereby any of the respective amounts written in the primary columns may be either added or subtracted by the 15 gross computing device at the will of the operator.

32. The combination of a traveling typewriter carriage with lugs (174) attached at intervals thereto, a gross computing mechanism, a traveling member (98*) moving therewith, a catch (162) attached to said traveling member and adapted to engage said lugs to enable said typewriter carriage to advance said traveling member step-by-step, an interceptor (179) adapted to trip or disconnect said catch from each lug to enable said catch to be engaged by the succeeding lug, a spring adapted to retract said traveling member, the said computing 30 device being arranged to either add or subtract, whereby any of the respective amounts written in the primary columns may be either added or subtracted by the gross computing device, at the will of the 35 operator.

33. The combination of a traveling typewriter carriage, with lugs attached thereto at intervals, a traveling gross computing mechanism having a traveling member (98*) moving therewith, a catch (162) attached to said traveling member and adapted to engage the said lugs to enable said carriage to advance said traveling member step-by-step, primary computing devices, an interceptor (179) adapted to trip or disconnect the catch (162) from each lug (174) to enable the same to be engaged by the succeeding lug, a spring adapted to retract said traveling member, the said gross computing mechanism being arranged to either add or subtract, whereby any of the respective amounts written in the primary columns may be either added or subtracted by the gross computing device, at the will of the 50 operator, and means for connecting any primary computing device to either add or subtract at will.

34. The combination with primary mechanism for adding numbers written in each of 60 a plurality of primary columns, so as to produce a footing or total of each individual column separately from the others, a primary master wheel actuating the same, secondary mechanism for simultaneously

computing the gross amount or cross footing of all the numbers written in the several columns respectively on each line across the page, and automatically computing the sum of all such cross amounts or cross footings, 65 and a secondary master wheel (97*) for actuating said secondary computing mechanism, the said secondary computing mechanism including gross computing wheels (98*), said primary mechanism including primary computing wheels (98), a typewriter carriage 70 connected so as to move said primary computing wheels bodily therewith when said carriage advances, thereby advancing said computing wheels past the said primary master wheel, and means for effecting repeated relative reciprocations between said secondary master wheel and the secondary computing wheels, during a single complete 75 relative movement or progress in one direction between said primary master wheel and all of the several primary computing wheels. 80

35. The combination with primary computing mechanisms for adding numbers written in each of a plurality of primary columns, so as to produce a footing or total of each individual column separately from the others, of secondary computing mechanism for simultaneously computing the gross amount or cross footing of all the numbers written in the several columns respectively on each line across the page, and simultaneously computing the sum of all such gross amounts or cross footings, 85 said primary mechanism including primary computing wheels, a primary master wheel 90 for actuating the same, said secondary computing mechanism including secondary computing wheels, a secondary master wheel for actuating the same, a typewriter carriage 95 connected with the primary computing wheels so that said computing wheels will have a step-by-step travel past the primary master wheel, and means for effecting repeated relative reciprocations between the secondary master wheel and the secondary computing wheels during a single complete 100 relative movement or progress in one direction between the single primary master wheel and all of the primary computing 105 wheels. 110

36. The combination with primary computing mechanism for adding numbers written in each of a plurality of primary columns, so as to produce a footing or total of each individual column separately from the others, of secondary computing mechanism for simultaneously computing the gross amount or cross footing of all the numbers written in the several columns respectively on each line across the page, and automatically computing the sum of all such gross amounts or cross footings, the said primary computing mechanism including 120 125

- primary computing wheels (98) arranged in column groups, the said secondary computing mechanism including secondary computing wheels (98), a primary master wheel actuating said primary computing wheels, a secondary master wheel actuating said secondary computing wheels, a typewriter carriage connected with the primary computing wheels so as to enable the same 5 to travel with said carriage, a rack in connection with said carriage, a gear co-operating with said rack, a second rack meshing with said gear, and a frame connecting said rack with said secondary master wheel so as to enable said secondary master wheel to travel in the opposite direction from said carriage, and means for effecting repeated 10 relative reciprocations between the secondary master wheel and the secondary computing wheels, during a single complete relative movement or progress in one direction between the single primary master wheel and all of the several primary computing wheels.
- 15 37. The combination with a typewriting mechanism having a traveling carriage, of a computing mechanism having a traveling element, means for moving said traveling element and said carriage concomitantly in opposite directions to effect their respective functions, and means enabling the return of said traveling element independent of said carriage.
- 20 38. The combination with a main computing mechanism, of a supplementary computing mechanism, connections to join said computing mechanisms, so as to have a concomitant action, said main computing mechanism having a greater capacity than said supplementary computing mechanism, and means for varying at will the point of attachment of said connections to bring said supplementary computing mechanism in synchronism with any portion of said main computing mechanism.
- 25 39. In a combined typewriting and computing machine, the combination with a typewriter carriage, of tabulator stops settable on said carriage, certain of said stops comprising effective lugs, a hook or latch, means for automatically connecting said hook or latch to said lugs to cause it to travel intermittently with said carriage, a motion-reversing device, one part of which is attached to said hook, and a denomination-selecting device which is attached to another part of said motion-reversing device.
- 35 40. In a combined typewriting and computing machine, the combination with a typewriter carriage and lugs settable at letter-space intervals on said carriage, of a latch or hook, means for intermittently connecting said hook to said lugs, a spring normally returning said hook, a denomination-selecting device, and a motion-reversing device connecting said latch or hook to said denomination-selecting device.
- 45 41. The combination with a traveling carriage, of a rack upon said carriage, tabulating stops adjustable along said rack, certain of said stops having effective lugs, a latch or hook, means to cause the hook to engage the lugs, means dependent upon the movement of the carriage for causing said hook to release the lugs in succession, a silencer for causing said hook to be ineffective with reference to said lugs, a master wheel, a gang of computing wheels, and means connected to said hook to effect relative traveling movement between said master wheel and said gang of computing wheels.
- 50 42. The combination with a carriage, of a rack upon said carriage, tabulating stops adjustable at letter-space intervals along said rack, certain of said stops having effective lugs, a latch or hook extending lengthwise of the rack and pivoted at one end, means at the other end of the hook to cause the hook to engage the lugs, means dependent upon the movement of the carriage for causing said hook to release the lugs in succession, a master wheel, a gang of computing wheels, and means connected to said hook to effect relative traveling movement between said master wheel and said gang of computing wheels.
- 55 43. The combination with a traveling carriage, of a rack upon said carriage, a latch or hook, tabulating stops adjustable on said rack, lugs on said stops, said lugs settable to effective or ineffective positions, means dependent upon the movement of the carriage for causing said hook to release the lugs in succession, a master wheel, a gang of computing wheels, and means connected to said hook to effect relative traveling movement between said master wheel and said gang of computing wheels.
- 60 44. The combination with a typewriter carriage, of tabulating mechanism including typewriter stops having lugs, a latch or hook, means for causing the latch or hook to engage and release the lugs in succession, a rod pivoted at one end to said hook, and computing mechanism including parts connected to the other end of said rod.
- 65 45. The combination with a typewriter carriage, of a rack connected to said carriage forming part of a tabulating mechanism, lugs adjustably mounted on said rack, a latch or hook to engage said lugs, a rod connected at one end to said hook, a computing mechanism having a traveling element connected to the other end of said rod, and means for causing said hook to engage and release said lugs in succession.
- 70 46. The combination with a typewriter carriage, of tabulating mechanism connected

- to said carriage, a hook engageable by said tabulating mechanism, resilient means for supporting said hook, and a computing mechanism having a traveling element connected to said hook, so that said tabulating mechanism may control the position of said traveling element. 65
47. The combination with a typewriter carriage, of a rack connected to said carriage forming part of a tabulator mechanism, members adjustable on said rack, certain of said members having effective lugs, a latch or hook, means to cause the hook to engage the lugs, means dependent on the movement of the carriage for causing said hook to release the lugs in succession, and computing mechanism including a part having a denomination-selecting movement, said part being connected to said hook. 70
48. In a combined typewriting and computing machine, the combination with a rack bar, of stops settable on said rack bar, lugs on said stops, a latch or hook, a spring normally urging said hook into the path of said lugs, a cam adapted to engage said hook at one end of its travel to positively move it out of the path of said lugs, and a spring normally returning said hook. 75
49. In a combined typewriting and computing machine, the combination with a typewriter carriage and a tabulating rack connected thereto, of stops settable on said rack comprising lugs, a latch or hook, a spring normally holding said latch or hook in the path of said lugs, a cam for positively moving said hook out of the path of said lugs when it is drawn by said lugs to one end of its travel, means for returning said hook to the opposite end of its travel, and computing mechanism comprising a denomination-selecting part connected to said hook. 80
50. In a combined typewriting and computing machine, the combination with a traveling carriage and a tabulating rack connected thereto, of lugs settable along said rack, a hook normally lying in the path of said lugs, a guide for said hook as it is drawn along by said lugs, a cam for positively moving said hook out of the path of its lugs at one end of its movement, and computing mechanism comprising a denomination-selecting device connected to said hook. 85
51. In a combined typewriting and computing machine, the combination with a traveling carriage, and a tabulating rack connected thereto, of lugs settable on said rack, a latch or hook, means for holding said latch or hook normally in the path of said lugs, a rod connected to said hook, and denomination-selecting means connected to said rod. 90
52. The combination with a typewriter carriage, of a latch or hook connected to a traveling member of a computing mechanism, means for effecting fine adjustments between said traveling member and said latch or hook, and means for automatically disconnecting said latch or hook from and re-connecting it to said carriage. 95
53. The combination with a typewriter carriage, of tabulating mechanism including tabulating stops having lugs, a latch or hook, means to cause the latch or hook to engage any of the lugs, means depending upon the movement of the carriage to cause the latch or hook to release any engaged lug, and computing mechanism including parts connected to said latch or hook. 100
54. In a computing machine, the combination with a key-controlled drive shaft, of a series of computing heads, each having a master-wheel shaft connected to said drive shaft, and means to enable said drive shaft to turn certain of said master-wheel shafts in either direction, and simultaneously turn certain of the remaining master-wheel shafts in the opposite direction. 105
55. In a computing machine, the combination with a key-controlled drive shaft, of a series of computing heads, each having a master-wheel shaft connected to said drive shaft, means to enable said drive shaft to turn certain of said master-wheel shafts in either direction, and simultaneously turn certain of the remaining master-wheel shafts in the opposite direction, and means for silencing certain of said master-wheel shafts. 110
56. In a computing machine, the combination with a key-controlled drive shaft, of a series of computing heads, each having a master-wheel shaft provided with a bevel gear, said drive shaft having a pair of bevel gears loose thereon, to mesh with each of said master-wheel bevel gears, and means to clutch said master-wheel shaft to any of the bevel gears thereon. 115
57. In a computing machine, the combination with a key-controlled drive shaft, of a series of computing heads, each having a master-wheel shaft provided with a bevel gear, said drive shaft having a pair of bevel gears loose thereon, to mesh with each of said master-wheel bevel gears, and means to clutch said master-wheel shaft to any of the bevel gears, thereon, said clutching means including independently operable individual clutches, one for each pair of bevel gears on said drive shaft. 120
58. In a computing machine, the combination with a key-controlled drive shaft, of a series of computing heads, each having a master-wheel shaft provided with a bevel gear, said drive shaft having a pair of bevel gears for each of said master-wheel bevel gears, and shiftable means co-operating with each pair of bevel gears on said drive shaft independently of the other gears thereon. 125

for enabling said drive shaft to rotate certain of said master-wheel shafts in either direction.

59. In a computing machine, the combination with a key-controlled drive shaft, of a series of computing heads, a master-wheel for each of said computing heads, a shaft to which each of said master-wheels is splined, means to connect each of said master-wheel
10 shafts to said drive shaft, means to move the master-wheels simultaneously along their shafts, and means for reversing certain of said master-wheel shafts independently of the others.
- 15 60. In a computing machine, the combination with a key-controlled drive shaft, of a series of computing heads, a master-wheel for each of said computing heads, a shaft to which each of said master-wheels is
20 splined, means to connect each of said master-wheel shafts to said drive shaft, means to move the master-wheels simultaneously

along their shafts, and means for either reversing or silencing certain of said master-wheel shafts independently of the others. 25

61. In a computing machine, the combination of a series of computing heads, a master-wheel for each of said computing heads, shafts to which said master-wheels are splined, one of said shafts for each master-wheel, a series of keys, means controlled by said keys for rotating said master-wheel shafts simultaneously, means to move the master-wheels simultaneously along their shafts, and means to silence certain of said 30 35 master-wheels.

In testimony whereof I have hereunto set my hand in the presence of two subscribing witnesses.

WALTER WRIGHT.
